UNITED STATES PATENT OFFICE.

SAMUEL BRONSTIEN, OF ST. PAUL, MINNESOTA.

WIRE FABRIC.

1,101,005.

Specification of Letters Patent. Patented June 23, 1914.

Application filed January 31, 1914. Serial No. 815,775.

To all whom it may concern:

Be it known that I, SAMUEL BRONSTIEN, a citizen of the United States, residing at St. Paul, in the county of Ramsey and State 5 of Minnesota, have invented certain new and useful Improvements in Wire Fabrics, of which the following is a specification, reference being had to the accompanying drawings.

10 This invention relates to certain improvements in wire fabrics and has relation more particularly to that class of fabrics employed for bottoms of beds, couches and the like; and an object of the invention is to 15 provide a device of this general character of a novel and improved construction and wherein are employed a plurality of wire units or links of duplicate formation.

It is also an object of the invention to 20 provide a bed fabric of this general character of a novel and improved arrangement possessing pronounced flexibility and so arranged that the weight imposed upon a part thereof does not affect the remainder of the 25 fabric.

Furthermore, it is an object of the invention to provide a fabric of this general character of a novel and improved arrangement which is substantially noiseless.

30 The invention also consists in the details of construction and in the combination and arrangement of the several parts of my improved wire fabric whereby certain important advantages are attained and the device 35 is rendered simpler, less expensive and otherwise more convenient and advantageous for use, all as will be hereinafter more fully set forth.

The novel features of the invention will 40 be carefully defined in the appended claim.

In order that my invention may be the better understood, I will now proceed to describe the same with reference to the accompanying drawings, wherein—

45 Figure 1 is a fragmentary view in top plan of a fabric constructed in accordance with an embodiment of my invention, and shown in applied position; Fig. 2 is an enlarged sectional view taken substantially on the line 2—2 of Fig. 1; Fig. 3 is an enlarged sectional view taken substantially on the line 3—3 of Fig. 1; Fig. 4 is a fragmentary view in perspective, illustrating the interlocking engagement between adjacent 50 strands as herein embodied; and Fig. 5 is a

view similar to Fig. 4 but illustrating a different interlocking engagement between adjacent units.

As disclosed in the accompanying drawings, 1 denotes one of the longitudinal side 60 bars of a bed frame and 2 and 3 the upper and lower end or cross bars, respectively, which bars, as herein disclosed, are conveniently and cheaply formed of angle bars and adapted to be suitably connected one to the 65 other in a conventional way. The cross bars 2 and 3 have their upstanding flanges apertured, as at 4, for the reception of the anchoring members 5 and 6 for the fabric proper, the members 5 being shown as hooks 70 while the members 6 are disclosed as helical springs to afford resiliency and elasticity, as is believed to be obvious to those skilled in the art to which my present invention 75 appertains.

Referring now to the fabric itself, in which the novel features of the present invention more particularly reside, this fabric is made up of a series of parallel longitudinal strands each formed of duplicate or 80 substantially duplicate bent wire units connected end to end, which units or links are provided intermediate their length with integral lateral extensions adapted to be interhooked midway of a link or unit in an 85 adjacent strand to connect the latter as well as form spaced filling elements for the support of the superimposed mattress.

Each of the units, as herein disclosed, is 90 formed from a single length of wire of suitable gage, according to the load to be sustained, which wire has its extremities bent inwardly to afford a pair of closely adjacent parallel longitudinal limbs 7, the overlapping portions of such inwardly directed extremities being laterally directed and interwoven, as at 8, with the free ends thereof spaced apart and formed into the rearwardly directed hooks 9—9 adapted to engage a limb 7 of an adjacent strand. 100

The adjacent extremities of the links or units of each strand are adapted to be interlocked and, as herein disclosed, I accomplish this purpose by having one extremity of the unit or link enlarged, as at 10, to afford 105 an eye while the opposite extremity of such unit or link is bent downwardly and rearwardly to afford a hook member 11 adapted to pass through the eye 10 of the adjacent unit or link. This arrangement I employ in 110

all the links or units except those units which are adapted to be engaged with the spring member 6 wherein the coacting extremities, as at 14, are straight. While I have specified these latter units as adapted 5 to be engaged with the anchoring members 6, it is to be observed that the arrangement of the strands could be reversed and they could be caused to engage with equal facility the members 5, herein disclosed as hooks.

10 From the foregoing, it will be observed that all of the links are substantially of duplicate construction except the units comprising one of the longitudinal edges of the fabric and wherein such units or links are 15 not provided with the laterally directed hook members, as is believed to be self-evident.

By having the links or units directed as 20 set forth and by having such links or units of one strand engage adjacent strands, as has hereinbefore been described, it will be readily perceived that the parallel limbs 7—7 permit such individual flexibility or 25 elasticity that when weight is put upon any part of the fabric, it does not in any way affect the remainder of the fabric. This I have conclusively demonstrated in actual 30 practice. I have also found that by having units or links constructed as herein set forth and assembled as disclosed, the fabric is substantially noiseless, which is a feature much to be desired.

As illustrated in Fig. 5, the parts are 35 identical as has been described relative to the remaining figures but it is to be observed that in interlocking the adjacent units, the hooks 9 are disposed across both of the limbs 7 and positioned to either side of the portion 40 8 whereby it will be observed that the engagement of the hooks 9 is with the outer

limb 7 in lieu of the inner limb, as disclosed in Fig. 4.

From the foregoing description, it is 45 thought to be obvious that a wire fabric constructed in accordance with an embodiment of my invention is of an extremely simple and comparatively inexpensive nature and is particularly well adapted for use by reason of the convenience and facility with 50 which it may be assembled and by reason of the effectiveness with which it performs its requisite functions; and it will also be obvious that my invention is susceptible of some change and modification without material departure from the principles and 55 spirit thereof, and for this reason I do not wish to be understood as limiting myself to the precise arrangement and formation of the several parts herein shown in carrying 60 out my invention in practice.

I claim:

A unit for wire fabric, formed from a single strand of material and comprising a pair of parallel longitudinal limbs, the ends 65 of the unit being provided with an eye and a hook respectively for inter-engagement with similar units, the extremities of the strand being connected at substantially the longitudinal center of one of the limbs, such connected portion being laterally disposed with the ends thereof separated and disposed in substantial parallelism and terminating in 70 hooks for engagement with a limb of the parallel adjacent unit.

In testimony whereof I hereunto affix my signature in the presence of two witnesses.

SAMUEL BRONSTIEN.
